UNITED STATES PATENT OFFICE.

SAMUEL DARLING, OF PROVIDENCE, RHODE ISLAND.

INKSTAND.

SPECIFICATION forming part of Letters Patent No. 367,136, dated July 26, 1887.

Application filed June 4, 1887. Serial No. 240,230. (No model.)

To all whom it may concern:

Be it known that I, SAMUEL DARLING, a citizen of the United States, residing at Providence, in the State of Rhode Island, have invented a new and useful Improvement in Inkstands, of which the following is a specification.

My invention relates especially to that class of inkstands which are provided with an elastic ink-fountain; and it consists in an inkstand having an elastic ink-fountain, a dip-cup, a case or frame made in two parts, which are connected to each other by means of a revoluble joint, one of the said parts being provided with an interior screw-thread, a follower-plate provided at its periphery with a screw-thread fitting the screw-threaded part of the case, and means for imparting a relative movement of rotation to the screw-threaded part of the case and the follower-plate, whereby the vertical height of the chamber for holding the elastic ink-fountain will be increased or diminished, thus controlling the ink-supply in the dip-cup.

Figure 1 is a vertical section of an inkstand embodying my improvement. Fig. 2 represents a top view of the follower-plate. Fig. 3 represents a top view of the lower and exterior part of the case. Fig. 4 is an enlarged detail section showing the construction of the revoluble joint between the upper and lower parts of the case. Fig. 5 represents an under view of the upper and interior part of the case.

In the accompanying drawings, A is the upper and interior part of the case, and B the lower and exterior part of the same, the cylindrical portion *a* of the part B being provided with an interior annular groove, *b*, and the cylindrical portion *c* of the part A being provided with the opposite exterior lugs, *d d*, which, upon forcing the part A within the cylindrical cavity of the part B, will spring into the said annular groove, and when so held the parts A and B of the case will be connected to each other by means of a revoluble joint. The part A at its lower interior portion is provided with a screw-thread, *e*, and the follower-plate C is provided at its periphery with a screw-thread adapted to fit the screw-thread *e*, and also with the perforations *ff*, adapted to receive the upwardly-projecting pins or studs *gg*, which are secured to the bottom plate, *h*,

of the part B of the case, so that if the part A is held stationary and the part B is revolved then the same revolution will be imparted to the follower-plate, which will rise or fall upon the pins or studs *gg* according to the direction of the revolving movement. The follower-plate C is also provided with a socket, *i*, adapted to receive the pivot *j* of the concaved bearing-plate D, which bears directly against the convex bottom portion, *k*, of the ink-fountain E; but when the bearing-surface *m* of the plate D is made smooth, the said plate can be made either integral with or rigidly secured to the part B of the case.

The neck *n* of the elastic ink-fountain E passes upward through the central opening, *o*, in the top plate, *p*, of the part A of the case, and is secured therein by means of the forcible insertion of the stem *q* of the dip-cup F, which serves to press the elastic neck of the fountain firmly against the wall of the opening *o*. The upwardly-projecting flange *r*, which surrounds the opening *o*, is provided with an external screw-thread, *s*, which is adapted to receive the interior screw-thread of the cap G, and at the upper interior portion of the cap G is placed the rubber packing-disk *t*, which serves to form a tight joint between the cap G and the upper surface of the dip-cup.

The cavity *u* in the dip-cup to receive the ink is made slightly tapering, and at its lower end is placed the removable pen-gage *v*, which serves to limit the movement of the pen when dipping for the ink, the opening *w* at the lower side of the pen-gage being made of less diameter than the width of the writing-pen.

The upward movement of the follower-plate caused by the relative rotation of the parts A and B of the case, by causing the compression of the ink-fountain, forces the ink upward into the cavity *u* of the dip-cup, and the reverse movement of the follower will cause the withdrawal of the ink from the said cavity. Upon screwing down the cap G, the cavity *u* of the dip-cup will be tightly closed, so that the inkstand can be either carried in the pocket or handled without danger of leaking.

I claim as my invention—

1. An inkstand having an elastic ink-fountain, a dip-cup, a case or frame made in two revoluble parts, which are connected to each other, one of the said parts being provided with

an interior screw-thread, a follower-plate provided at its periphery with a screw-thread fitting the screw-threaded part of the case, and means for imparting a relative movement of 5 rotation to the screw-threaded part of the case and the follower-plate, whereby the vertical height of the chamber for holding the ink-fountain will be varied, thus controlling the ink-supply in the dip-cup, substantially as described.

2. An inkstand having an elastic ink fountain, a dip-cup, a case or frame made in two revoluble parts, which are connected to each other by means of an annular groove and projecting lugs, the inner cylindrical portion of the case being provided with an interior screw-thread, a follower-plate provided at its periphery with a screw-thread fitting the screw-thread of the inner portion of the case, a stud 15 projecting upward from the bottom part of the case and engaging with the follower-plate, whereby upon imparting a relative movement of rotation to the screw-threaded part of the case and the follower-plate the vertical height 20

of the chamber which holds the ink-fountain 25 will be varied, thus controlling the ink-supply in the dip-cup, substantially as described.

3. An inkstand having an elastic ink-fountain, a dip-cup, a case or frame made in two revoluble parts, which are connected to each other by means of an annular groove and projecting lugs, the inner cylindrical portion of the case being provided with an interior screw-thread, a follower-plate provided at its periphery with a screw-thread fitting the screw-thread of the inner portion of the case, and means for imparting a relative movement of rotation to the screw-threaded part of the case and the follower-plate, whereby the vertical height of the chamber for holding the ink-fountain will be raised, thus controlling the ink-supply in the dip-cup, substantially as described. 30 40
